UNITED STATES PATENT OFFICE.

HARRY RANDOLPH VAN DEVENTER, OF NEWARK, NEW JERSEY, ASSIGNOR TO SPLITDORF ELECTRICAL COMPANY, OF NEWARK, NEW JERSEY, A CORPORATION OF NEW JERSEY.

IGNITION DEVICE FOR INTERNAL-COMBUSTION ENGINES.

1,370,934.

Specification of Letters Patent.

Patented Mar. 8, 1921.

Application filed April 7, 1919. Serial No. 288,100.

To all whom it may concern:

Be it known that I, HARRY RANDOLPH VAN DEVENTER, a citizen of the United States, residing at Newark, in the county of Essex, State of New Jersey, have invented a certain new and useful Improvement in Ignition Devices for Internal-Combustion Engines, of which the following is a description, reference being had to the accompanying drawing and to the figures of reference marked thereon.

The invention relates to new and useful improvements in ignition devices for internal combustion engines, and more particularly to an ignition device which includes a fixed and a movable electrode, and a magneto generator for supplying current for ignition.

An object of the invention is to provide an ignition device of the above character, wherein the current generating member of the magneto is operated by a spring adapted to be placed under tension by the engine, and wherein said spring which actuates the current generating member also operates to maintain the electrodes in contact.

A further object of the invention is to provide a device of the above character, wherein the spring which maintains the electrodes in contact also operates to hold the movable electrode on its seat.

A further object of the invention is to provide an ignition device of the above character, wherein the current generating member is actuated by a spring operated trip lever and yielding means is provided for limiting the movement of said trip lever, said spring also serving to hold the electrodes in contact.

A still further object of the invention is to provide a magneto ignition device of the above character, wherein the movable electrode turns about an axis in alinement with the axis of the movable current generating member, and wherein a spring is utilized for operating the trip lever which actuates the current generating member and the movable electrode, and wherein said spring also operates to hold the electrodes in contact and the movable electrode on its seat.

These and other objects will in part be obvious and will in part be hereinafter more fully described.

In the drawings which show by way of

illustration one embodiment of the invention—

Figure 1 is a view partly in side elevation and partly in section, showing a magneto ignition device embodying my improvements;

Fig. 2 is a view partly in top plan and partly in section of the same;

Fig. 3 is an end view of the device with the generator removed;

Fig. 4 is a detail, showing the trip lever and the supporting sleeve therefor, in side elevation;

Fig. 5 is a similar view, but showing the parts in end elevation;

Fig. 6 is a side view showing the sleeve carried by the movable electrode which is operated upon by the trip lever for separating the electrodes;

Fig. 7 is an end view of the same.

The invention consists broadly in an ignition device having a movable and a fixed electrode and a magneto generator for supplying current for ignition. The magneto generator is provided with a current generating member which is oscillated in a magnetic field for producing the current for ignition. This movable current generating member is connected to a trip lever. The movable electrode is carried by a short shaft mounted in a suitable igniter block or bracket, and this shaft is in alinement with the shaft carrying the movable generating member of the magneto generator. Mounted on the shaft of the movable electrode is a fixed sleeve. This fixed sleeve and the trip lever are provided with coöperating parts, which, when brought into engagement, will cause a positive movement to be imparted from the trip lever to the movable electrode. A spring is connected to the trip lever and the sleeve on the movable electrode and operates to perform several functions. First, this spring is the main actuating spring for the trip lever; second, this spring serves as a means for holding the electrodes in contact; and, third, said spring serves as a means for holding the movable electrode firmly against its seat. A yielding buffer is provided for limiting the movement of the trip lever, so that the engaging parts between this trip lever and the sleeve on the movable electrode are normally separated a sufficient distance, so as to permit the spring

operating upon the trip lever at one end as an abutment to hold the electrodes in contact. These engaging parts, however, are so positioned that the overthrow of the trip lever will compress the buffer sufficiently so as to bring these parts into engagement and thus positively separate the electrodes.

Another feature of the invention is the manner of supporting the parts described 10 above. The electrodes are mounted on one supporting bracket and the movable generator is mounted upon the other supporting bracket. These brackets are independent of each other, although preferably secured to 15 the engine cylinder by the same bolts.

The invention will possibly be made more clear by a brief reference to the drawings, wherein I have shown the ignition device as consisting of a magneto generator G, 20 which is mounted upon a supporting bracket 1. Associated with this magneto generator is a fixed electrode 2, and a movable electrode 3. The movable electrode 3 includes an arm 4, mounted on a shaft 5. 25 The electrodes are mounted in an igniter block or supporting bracket 6. Said igniter block has a laterally projecting flange 7 provided with bolt holes through which the bolts 8-8 extend. Said igniter block or 30 bracket is formed with a forwardly projecting portion 9, which is adapted to fit snugly within an opening 10 formed in the supporting base plate 11 of the bracket 1. The bracket 1 is preferably formed of sheet 35 metal and is provided with parallel arms 12-12 which extend outwardly from the supporting base plate 11, and these arms 12-12 form a shelf on which the magneto generator is bolted by suitable bolts 13-13.

40 The bolts 13-13 extend through lugs 14-14 projecting laterally from the arms 12-12. This specific sheet metal bracket, however, forms no part *per se* of my present invention. The base plate 11 is provided with 45 openings for the bolts 8-8 and these bolts, therefore, serve to secure both brackets to the engine cylinder. The projecting portion 9 of the bracket 6 serves as a means for holding the two brackets in fixed relation to each other and prevents any possible 50 shifting of one bracket relative to the other during the operation of the machine and also insures that the brackets shall be returned to exactly the same place on the engine cylinder as when removed for the purpose of cleaning the electrodes. It will be noted that when the brackets are removed, as they are independent, they will readily 55 separate from each other, and some means is necessary in order to insure that they be returned to the same fixed position, so that the synchronism of the parts may be insured.

The fixed electrode 2 is mounted in a suitable support formed as a part of the igniter

block 6 and is provided at its outer end with a terminal connection 15 for a wire 16 leading to the magneto generator. The other electrode, as is usual in this type of ignition device, is grounded on the engine cylinder. 70 The shaft 5 carries the movable electrode, extends through the igniter block and projects forwardly therefrom for a short distance. Fixed to this shaft is a sleeve 17. Said sleeve may be keyed or otherwise secured to the electrode shaft. The magneto generator is provided with a current generating member which may be in the form of a rotor of any character, and the shaft of this rotor is indicated at 18 in Fig. 1 of the 80 drawings. Said shaft projects from the magneto generator a slight distance and fixed to the end of the shaft is a trip lever 19. Said trip lever is keyed to the shaft so as to turn with the shaft. Said trip lever, 85 also, has a downwardly projecting arm 20. This arm 20 projects laterally, as indicated at 21, where it is provided with a shoulder 22 adapted to be engaged by the push rod, which is indicated in dotted lines at 23 in 90 Fig. 3 of the drawings. The lateral portion 21 of the arm 20 has a forwardly projecting knock off arm 24. As the trip lever moves forward, it engages the shoulder and swings the trip lever. The knock off arm 95 24 engaging the push rod forces the same downward and finally disengages the same from the shoulder 22.

Encircling the shaft of the movable electrode is a coil spring 25. This coil spring at 100 one end is hooked about a pin 26, carried by the sleeve 17. The other end of the spring is hooked about the arm 20. This spring is put under slight lateral or endwise tension, so that the spring operating at one end 105 against the trip lever 19 as an abutment serves to draw the sleeve 17 toward the trip lever and as the sleeve is keyed to the movable electrode shaft, it forces the electrode against its seat in the igniter block or 110 bracket and thus forms a very tight joint about the moving parts of this electrode.

The trip lever 19 is provided with a projecting portion at 27, which forms a shoulder 28. The sleeve 17 extends within the 115 coil spring 25 and is also provided with a projecting portion 29. The projecting portion 29 lies in the same vertical plane as the projecting portion 27, and has a shoulder 30 which is adapted to be engaged by the shoulder 28 of the trip lever when said trip 120 lever is under movement by the spring 25, as will be hereinafter more fully disclosed.

Mounted on the bracket 1, and projecting upwardly therefrom, is a post 31. In the 125 upper end of this post 31 is located a buffer 32. Said buffer is formed with an enlarged head adapted to move in a recess in the bracket and a spring 33 seated against this head and the bottom of the recess normally 130

forces the buffer outwardly to a point determined by the nut 34, which limits the movement of this buffer by the spring. This buffer spring is very stiff and is of greater tension than the spring 25—particularly when the parts are in normal position. The arm 20 is adapted to strike and normally rest against the buffer 32. When this arm is resting against the buffer, the shoulder 28 is slightly out of engagement with the shoulder 30. The coil spring 25 forces the arm 20 against the buffer which serves as an abutment and a limiting stop for the movement of the trip lever. This coil spring is also adapted to turn the movable electrode in a clockwise direction and as the shoulders 28 and 30 are out of engagement, the electrode shaft will be limited by the movable electrode coming into contact with the fixed electrode, so that under normal conditions and before the parts are actuated, the spring 25 performs the double function of holding the movable electrode seated and the electrodes in contact. When the push rod 23 moves forward, it engages the trip lever and turns the same in a clockwise direction, as viewed in Fig. 3. This puts the spring 25 under increasing tension as the arm moves. This movement of the trip lever carries the shoulder 28 away from the shoulder 30 and also serves to press the contacts very firmly into engagement, thus insuring a perfect contact between the electrodes. When the push rod is knocked from the shoulder 22 and releases the trip lever, the spring 25 will oscillate the trip lever very rapidly, turning the current generating member which is in fixed connection therewith, and just as the current reaches a maximum peak, the shoulder 28 will strike the shoulder 30 and positively turn the sleeve 17, rotating the movable electrode and separating the electrodes to produce the spark. The buffer 32 yields sufficiently to permit these shoulders 28 and 30 contacting and the electrodes to be separated, notwithstanding that the spring 33 is normally of greater tension than the spring 25, for the reason that the spring 25 is put under greater tension as the push rod turns the trip lever and through the momentum of the parts actuated by the spring under this greater tension, the spring 33 will be compressed and permit a sufficient overthrow to bring about the result stated.

From the above, it will be understood that I have provided an ignition device, wherein the number of parts has been reduced to a minimum and a single actuating spring used for oscillating the current generating member, the movable electrode for holding the electrodes normally in contact and for seating the movable electrode. It will also be noted that the movable electrode shaft is in alinement with the axis of the current generating member and the trip le-

ver, and, therefore, when the shoulder 28 engages the shoulder 30, there will be no rubbing or sliding of the one on to the other. There is a direct positive engagement and a forward movement of the shoulder 30 in the same direction as the movement of the shoulder 28. This avoids any wear at this point of contact between the trip lever and the member on the movable electrode. It will also be noted that the parts are free from all adjusting features, so that when once properly timed and constructed, there are no adjustments which can be tampered with and thus the parts thrown out of proper adjustment. While I have shown a shoulder engagement between the trip lever and the sleeve on the movable electrode, it will be understood, of course, that other devices may be used for imparting this positive movement from the trip lever to the movable electrode. It will also be understood that various modifications may be made in the details of construction without departing from the spirit of the invention, as set forth in the appended claims.

Having thus described my invention, what I claim as new and desire to secure by Letters Patent, is:

1. In an ignition device, a fixed and a movable electrode, a magneto generator having a current generating member, a trip lever connected to said current generating member, a spring connected to the trip lever for actuating the same, means actuated by the overthrow of the trip lever for separating the electrodes, and means whereby said spring normally holds said electrodes closed.
2. In an ignition device, a fixed and a movable electrode, a magneto generator having a current generating member, a trip lever connected to said current generating member, a spring connected to the trip lever for actuating the same, means actuated by the overthrow of the trip lever for separating the electrodes, means whereby said spring normally holds said electrodes closed, and means whereby said spring for actuating the trip lever holds the movable electrode on its seat.
3. In an ignition device, a fixed and a movable electrode, a magneto generator having a current generating member, a trip lever connected to said current generating member, a yielding buffer for limiting the movement of the trip lever, a spring connected to the trip lever for actuating the same, means for connecting said spring to the movable electrode, whereby said spring normally holds the electrodes in contact, and positive means for imparting the overthrow movements of the trip lever to the movable electrode for separating the same.
4. In an ignition device, a fixed and a movable electrode, a magneto generator having a current generating member, a trip lever

- connected to said current generating member, a yielding buffer for limiting the movement of the trip lever, a spring connected to the trip lever for actuating the same, means for connecting said spring to the movable electrode, whereby said spring normally holds the electrodes in contact, and positive means for imparting the overthrow movements of the trip lever to the movable electrode for separating the electrodes, said spring being disposed so as to hold the movable electrode on its seat.
5. In an ignition device, a fixed and a movable electrode, a magneto generator having a current generating member, the shaft of which is in alinement with the shaft of the movable electrode, a trip lever mounted on the shaft of the current generating member, a spring for actuating the trip lever, a sleeve on the shaft of the movable electrode, said spring being connected to said sleeve and to the trip lever and operating normally to hold the contacts closed, engaging parts carried by the sleeve and the trip lever, a yielding buffer for limiting the movement of the trip lever so as to hold said engaging parts separated, whereby the spring will normally hold the contacts together.
10. In an ignition device, a fixed and a movable electrode, a bracket for separating the same, said spring being disposed so as to hold the movable electrode on its seat.
15. In an ignition device, a fixed and a movable electrode, a magneto generator having a current generating member, the shaft of which is in alinement with the shaft of the movable electrode, a trip lever mounted on the shaft of the current generating member, a spring for actuating the trip lever, a sleeve on the shaft of the movable electrode, said spring being connected to said sleeve and to the trip lever and operating normally to hold the contacts closed, engaging parts carried by the sleeve and the trip lever, a yielding buffer for limiting the movement of the trip lever so as to hold said engaging parts separated, whereby the spring will normally hold the contacts together.
20. In an ignition device, a fixed and a movable electrode, a bracket in which said electrodes are mounted, a magneto genera-
25. In an ignition device, a fixed and a movable electrode, a magneto generator having a current generating member, the shaft of which is in alinement with the shaft of the movable electrode, a trip lever mounted on the shaft of the current generating member, a spring for actuating the trip lever, a sleeve on the shaft of the movable electrode, said spring being connected to said sleeve and to the trip lever and operating normally to hold the contacts closed, engaging parts carried by the sleeve and the trip lever, a yielding buffer for limiting the movement of the trip lever so as to hold said engaging parts separated, whereby the spring will normally hold the contacts together.
30. In an ignition device, a fixed and a movable electrode, a bracket in which said electrodes are mounted, a magneto genera-
- tor, an independent bracket on which said magneto generator is mounted, said brackets having interengaging parts for holding the same in fixed relation to each other, said generator having a current generating member, a trip lever for actuating the same, a spring for operating said trip lever, yielding means for limiting the movement of the trip lever, and means for positively imparting the overthrow movements of the trip lever to the movable electrode for separating the electrodes, said spring being connected to the movable electrode and normally holding the electrodes in contact.
7. In an ignition device, a fixed and a movable electrode, a bracket in which said electrodes are mounted, a magneto generator, an independent bracket on which said magneto generator is mounted, said brackets having interengaging parts for holding the same in fixed relation to each other, said generator having a current generating member, a trip lever connected to said current generating member, a spring connected to the trip lever for actuating the same, means actuated by the overthrow of the trip lever for separating the electrodes, and means whereby said spring normally holds said electrodes closed.

In testimony whereof I affix my signature.
HARRY RANDOLPH VAN DEVENTER.
